(57) **CLAIM**

The ornamental design for a body scanner, as shown and described.

DESCRIPTION

FIG. 1 is a front perspective view of a body scanner;
FIG. 2 is a rear perspective view thereof;
FIG. 3 is a front view thereof;
FIG. 4 is a rear view thereof;
FIG. 5 is a right side view thereof;
FIG. 6 is a left side view thereof;
FIG. 7 is a top plan view thereof;
FIG. 8 is a bottom plan view thereof;
FIG. 9 is a close-up perspective view of a portion thereof;
and,
FIG. 10 is another close-up perspective view of the portion thereof.

The broken lines in the drawings show portions of the body scanner that form no part of the claimed design.
